ABSTRACT OF THE DISCLOSURE

A freely rotatable drum having a plurality of electrical brush-like contacts biased into engagement with the surface thereof and conducting material situated on the outer surface to provide an electric circuit between predetermined sets of said stationary contacts for predetermined angular orientations of said drum with a motor attached to said drum and energizable through a set of electrical contacts in a timer, said brush-like contacts being connected to a plurality of indicators energizable through a second set of contacts in the timer subsequent to stopping of the motor after energization thereof so that the indicators are energized in a purely random fashion according to the angular orientation of the drum upon the stopping thereof after energization of the motor. The motor is constructed with substantially no braking or damping therein except the normal components of friction.

This invention pertains to a device which can be utilized in advertisement while simultaneously providing some amusement to the viewer and more specifically to a device which periodically attracts attention to any one of a group of advertising pictures or the like in a purely random fashion.

In the advertising field there are a great variety of devices which cause portions of advertisements to move or light up or in some other way attract the viewer's attention. All of these devices operate sequentially so that once the viewer has seen a complete sequence of operations he loses interest and the advertisement no longer can hold his attention.

The present device has a plurality of advertisements, such as pictures, trademarks, etc., positioned therein with means for periodically indicating any one of the plurality so that a viewer's attention is attracted to one advertisement at a time. For example, the advertisements may be placed in rows with individually energized light sources positioned behind each advertisement. The present device has means therein for randomly energizing a single light source for a desired period of time to draw attention to the associated advertisement. That light source is then de-energized and after a short period of time a second light source is energized. This procedure continues periodically as long as the device is connected to a source of energy.

Thus, the present device will hold a viewer's interest for an indefinite period of time since the activation of the various advertisements will not be sequential. Even though a viewer has seen the device many times before, he will invariably have a tendency to stop and attempt to determine which advertisement will be activated next. The present device will add a degree of amusement to an advertising device and, therefore, will enhance the effectiveness of the advertisements. It also should be noted that the present device could be used for a child's game by substituting numbers or letters for the advertisements.

It is an object of the present invention to provide a new and improved advertisement device.

It is a further object of the present invention to provide

2

an advertisement device having incorporated therein an amusement factor which will enhance the effectiveness of the advertisement.

It is a further object of the present invention to provide a device which periodically completes any one of a plurality of possible circuits in a purely random fashion.

These and other objects of this invention will become apparent to those skilled in the art upon consideration of the accompanying specification, claims, and drawings.

Referring to the drawings wherein like characters indicate like parts throughout the figures.

FIG. 1 is a perspective view of the present device assembled;

FIG. 2 is a schematic diagram of the electrical circuitry in the present device;

FIG. 3 is a view in perspective of the rotary switch utilized in the present device;

FIG. 4 is a development of the cylinder in the switch of FIG. 3; and

FIG. 5 is a schematic diagram of another embodiment of the electrical circuitry.

In FIG. 1 the numeral 10 designates a box-like container having the electrical circuitry therein, which will be explained presently. The container 10 has a switch 11 and a fuse holder, with the associated fuse 12 therein, operatively attached to the front thereof. A second box-like container 13 has the indicating devices therein operatively attached to the electrical circuitry in the container 10. In this embodiment the indicating devices are a plurality of light sources 14 through 19 positioned behind a similar number of transparent panels or openings 20 through 25. The transparent panels 20-25 may contain advertisements or the like which will be illuminated by the light sources 14-19 when the light sources 14-19 are energized.

In FIG. 2 the power switch 11 and fuse 12 are connected in series and one side thereof is adapted to be connected to a suitable source of power through a lead 30. The other side of the series connection of switch 11 and fuse 12 is connected to a junction 31. A second junction 32 is adapted to be connected to the other side of the power source by a lead 33. Timing means, generally designated 35, in this embodiment include a synchronous motor 36, a first movable contact 37 with an associated stationary contact 38 and a second movable contact 39 with an associated stationary contact 40. The synchronous motor 36 is connected to the junctions 31 and 32 by a pair of leads 41 and 42 respectively. The movable contacts 37 and 39 are connected to junction 31 by a pair of leads 43 and 44 respectively.

The synchronous motor 36 has an activating pin 45 which operates in a fashion similar to a cam to engage the movable contacts 37 and 39 and cause them to engage the fixed contacts 38 and 40 respectively for each revolution thereof. In general the activating pin 45 is connected to the synchronous motor 36 so that it revolves at a relatively slow rate. An example of a desirable rate of rotation is one revolution per minute. The movable contacts 37 and 39 are positioned relative to the activating pin 45 so that the movable contact 39 is engaged first. The movable contact 39 is constructed so that the length of time the activating pin 45 is engaged therewith is of a substantial magnitude. As an additional feature this length of time may be variable if desired. At some time subsequent to the engagement of the movable contact 39 the activating pin 45 engages the movable contact 37. Again the length of time which the activating pin 45 is engaged with the movable contact 37 is of a substantial magnitude and may be varied if desired. The period of time between the engagement of the activating pin 45 with the movable contact 39 and the engagement of the

activating pin 45 with the movable contact 37 will be discussed in more detail later.

The stationary contact 40 of the timing means 35 is attached by means of a lead 49 to a lead 50 of a rotary motor 51. A second lead 52 of motor 51 is attached to a junction 53 by means of a lead 54. The junction 53 is in turn attached to the junction 32 by means of a lead 55. Thus, when the movable contact 39 engages the stationary contact 40 a circuit is completed connecting the motor 51 to the energizing source and motor 51 will operate until the movable contact 39 is disengaged from the stationary contact 40. In general the motor 51 does not have any braking or damping means attached thereto so that once the motor is de-energized it will continue to rotate until the natural frictional components therein cause it to stop.

The rotation of the motor 51 after it is de-energized will be for an undetermined but relatively short period of time. The movable contact 37 is positioned relative to the synchronous motor 36 and activating pin 45 so that it will be engaged at some time subsequent to the stopping of the motor 51. In general if the movable contacts 39 and 37 are placed approximately 180 mechanical degrees apart in the path of the activating pin 45 there will be sufficient time for the motor 51 to stop after the activating pin 45 has disengaged the movable contact 39 and before it engages the movable contact 37.

A rotary switch 60 is connected to the motor 51 for rotation therewith by means of a shaft 61. The rotary switch 60 can be seen in detail in FIGS. 3 and 4. The switch 60 has a housing not shown which includes a pair of disk shaped end members 62 and 63. The end members 62 and 63 are maintained in a coaxial spaced apart relationship by a plurality of spacers 64 which are attached to the end members 62 and 63 by means of bolt 65 or the like. The shaft 61 is mounted approximately coaxial with the members 62 and 63 and for relative rotation with respect thereto by bearing means positioned within the end members 62 and 63. A cylindrical drum 66 is fixedly attached to the shaft 61 and positioned between the end members 62 and 63 for relative rotation with respect thereto. A development of the surface of the drum 66 is illustrated in FIG. 4.

The drum 66 has a first strip 67 of conducting material on the surface thereof positioned adjacent the left edge and completely encircling the circumference thereof. Six arcuate segments of conducting material each having a length substantially equal to 60° of the circumference of the drum 66 are designated 68-73. The arcuate segments 68-73 are positioned on the surface of the drum 66 so that each segment 68-73 lies in a plane spaced longitudinally from the previous segment but parallel and adjacent. In addition, the segments 68-73 are spaced about the circumference of the drum 66 so as to include successive 60° portions of the circumference. That is, the arcuate segment 68 includes the first 60° of the circumference of the drum 66 and lies adjacent and parallel to the strip 67. The second arcuate segment 69 lies between 60° and 120° on the circumference of the drum 66 and parallel but spaced longitudinally from the segment 68. In a like manner the segment 70 lies between 120° and 180° on the surface of the drum 66 and is parallel but spaced longitudinally from the segment 69. The segments 71, 72 and 73 lie between 180°-240°, 240°-300° and 300°-360° respectively. In addition each of the segments 68-73 are electrically connected together and to the strip of material 67. This may be accomplished by having adjacent segments in contact or through internal wires or the like.

A block 75 has seven fingers 76-82 mounted therein and extending outwardly perpendicular to the longitudinal axis thereof. The block 75 is mounted between the end members 62 and 63 of switch 60 so that the fingers 76-82 ride lightly on the surface of the drum 66. The fingers 76-82 are constructed of an electrical conductor

with a slight resilience so that they are maintained in mechanical contact with the surface of the drum 66. The fingers 76-82 are spaced apart longitudinally so that the finger 76 lies in the plane of the arcuate conducting strip 67 while the fingers 77-82 lie in the planes of the segments 68-73 respectively. Thus, as the drum 66 rotates the finger 76 is always in contact with the conducting strip 67 and one of the fingers 77-82 will always be in contact with one of the conducting segments 68-73 but the particular segment 68-73 in contact with a finger 77-82 respectively will change for each 60° of rotation of the drum 66. Since the strip 67 and the segments 68-73 are all electrically connected together on the surface of the drum 66 an electrical circuit is completed from the finger 76 through the strip 67 to the particular finger 77-82 in contact with its associated segment 68-73.

Referring to FIG. 2 a lead 85 connects the finger 76 of switch 60 to the stationary contact 38 of timing means 35. Six leads 86-91 connect the six fingers 77-82 to one side of the light sources 14-19 respectively. The opposite side of the light sources 14-19 are connected to the terminal 53 by means of leads 92-97 respectively.

In the operation of the present device, the leads 30 and 33 are connected to a suitable power source and the switch 11 is closed. This energizes the timing means 35 and synchronous motor 36 begins to rotate. As the activating pin 45 engages the movable contact 39 contacts 39 and 40 close completing a circuit to the motor 51. The motor 51 and the rotary switch 60 rotate under power until the activating pin 45 is disengaged from the movable contact 39 and contacts 39 and 40 open. The motor 51 and rotary switch 60 continue to rotate for a short period of time until stopped by the natural frictional components therein. As the activating pin 45 rotates 180° it engages the movable contact 37 which closes the contacts 37 and 38 completing a circuit to the finger 76 of the rotary switch 60. Since the rotary switch 60 is stopped one of the fingers 77, 82 are in contact with its associated arcuate segment 68-73 respectively. As illustrated in FIG. 2 the finger 82 is in contact with its associated arcuate segment 73 and a circuit is completed from the finger 76 to the light source 19. Thus, the light source 19 is energized and the panel 25 is illuminated until the activating pin 45 rotates a sufficient distance to disengage the movable contact 37. In this fashion, the panels 20-25 are illuminated in a purely random fashion.

In FIG. 5 an alternate embodiment is illustrated in which similar members are indicated with similar numbers having a prime added. In this embodiment the energy for the light sources 14'-19' does not flow through the conducting material on the surface of the switch 60'. The basic circuitry is similar to that illustrated in FIG. 2 except that a direct current power supply generally designated 100' and seven relays designated 101'-107' are included, as will be described presently. The power supply 100' has a transformer designated 108' with a primary winding 109' and a secondary winding 110'. The primary winding 109' is connected to the terminals 31' and 32' by a pair of leads 111' and 112' respectively. One side of the secondary winding 110' is common to all of the circuitry and is designated 113'. The other side of the secondary winding 110' is connected to one side of a diode 114' the other side of which is connected to a junction point 115'. A filter capacitor 116' is connected between the junction 115' and the common line 113'. A dropping resistor 117' is connected between the junction point 115' and a second junction point 118'. A capacitor 119' is connected from the junction point 118' to the common line 113' to filter any surges of current at the junction 118'. A filter resistor 120' is connected between the junction point 115' and a junction point 121'. A filter capacitor 122' is connected between the junction point 121' and the common line 113'. A load resistor 123' is connected in parallel with the filter capacitor 122' between the junction 121' and the common line 113'.

The lead 52' of the motor 51' is connected to the common line 113' by the lead 54'. The lead 50' of the motor 51' is connected to the movable contact 39' by the lead 49'. The stationary contact 40' associated with the movable contact 39' is connected to the junction 118' by a lead 125'. The second movable contact 37' is connected to the junction 121' by a lead 126' while the associated stationary contact 38' is connected to one side of the coil 101A of relay 101' by a lead 127'. The other side of the coil 101A is connected to the common line 113' by a lead 128'. A capacitor 129' is connected in parallel with coil 101A to suppress any surges of current therethrough. Thus, when the actuating pin 45' engages the movable contact 39' and contacts 39' and 40' are closed a circuit is completed which connects the motor 51' to an output, at junction 118', of the power supply 100'. When the actuating pin 45' disengages the movable contact 39' and engages the movable contact 37' a circuit is completed connecting the relay coil 101A to the output of the power supply 100' at junction 121'. The relay 101' has a pair of contacts 101B one of which is connected to the junction 121' by a lead 130' and the other of which is connected to the finger 76' of switch 60' by a lead 85'. A capacitor 134' is connected between the lead 85' and return line 113' to remove any surges of current from the lead 85' when the contacts 101B open. When the coil 101A of relay 101' is energized by the closure of contacts 37' and 38' the contacts 101B close completing a circuit from the power supply 100' to the finger 76' of the switch 60'.

Each of the fingers 77-82 are connected to one side of the relay coils 102A-107A of the relays 102'-107' respectively. The other side of the coils 102A-107A are connected to the common line 113' by a lead 131'. A lead 133' is connected from a tap 132' on the secondary winding 110' of the transformer 108' to one side of each of the sets of contacts 102B-107B of the relays 102'-107' respectively. The other side of each of the contacts 102B-107B is connected to one side of the light sources 19'-14' respectively. The other side of the light sources 19'-14' are connected to the common line 113' by leads 97'-92' respectively. Thus, whenever the activating pin 45' engages the movable contact 37' the relay 101' is activated and contacts 101B close applying power to the finger 76' of the switch 60'. At this time one of the fingers 77'-82' is in contact with the associated arcuate segment 68'-73' and a circuit is completed through the switch 60'. In FIG. 5 the arcuate segment 73' is in contact with the finger 82'. Thus, when the contacts 101B close a circuit is completed through the coil 102A closing the contacts 102B and completing a circuit from the tap 132' of the secondary winding 110' through the lead 133', contacts 102B, light source 19', lead 97' and the common line 113'. The timing means 35', motor 51' and the rotary switch 60' operate in a fashion similar to that explained in conjunction with FIG. 2.

Thus, by placing various desirable advertisements or the like in overlying positions on the panels 20-25 the present device will periodically draw the viewer's attention to one of the advertisements, which advertisement will be selected by the present device purely at random. Because of this random selection of advertisements a viewer's interest will be increased and the effectiveness of the advertisement will be greatly enhanced. It should be understood that light sources have been illustrated in the present embodiment for purposes of explanation but other apparatus for indicating the various advertisements might

be utilized. For example, moving objects in the advertisement, moving the entire panel, etc.

While we have shown and described a specific embodiment of this invention, further modifications and improvements will occur to those skilled in the art. We desire it to be understood, therefore, that this invention is not limited to the particular form shown and we intend in the appended claims to cover all modifications which do not depart from the spirit and scope of this invention.

What is claimed is:

1. An advertisement and amusement device comprising:

- (a) rotary motor means;
- (b) rotary switch means having a rotatable drum connected to said motor means for rotation therewith and having a plurality of sets of stationary contacts biased into engagement with the surface of said drum and conducting material at the surface of said drum situated to provide an electrical circuit between predetermined sets of said stationary contacts for predetermined angular orientation of said drum, said conducting material being affixed to the drum so the outer surface of said drum is relatively smooth and continuous;
- (c) timing means having a first pair of contacts one of which is connected to said motor means and the other of which is adapted to be connected to an energizing source and a second pair of contacts one of which is connected to said rotary switch means and the other of which is adapted to be connected to an energizing source, said timing means periodically closing said first pair of contacts for a predetermined period of time whereby said motor means is energized and subsequent to the stopping of said motor means said second pair of contacts are closed for a predetermined period of time; and
- (d) indicating means operatively connected to said sets of contacts of said rotary switch means for indicating which set of contacts of said rotary switch means is closed when a circuit is completed to the energizing source through said second pair of contacts of said timing means.

2. An advertisement and amusement device as set forth in claim 1 wherein the sets of contacts of said rotary switch means are positioned so only one set of contacts of said rotary switch means is closed at any one given time.

3. An advertisement and amusement device as set forth in claim 1 wherein the rotary motor means is constructed with substantially no braking or damping therein except the normal components of friction.
